ATTORNEYS

UNITED STATES PATENT OFFICE

ARTHUR J. SLINGERLAND, OF CHICAGO, ILLINOIS

WINDOW FASTENER

Application filed February 3, 1928. Serial No. 251,619.

My invention relates to improvements in fastening devices, and it consists in the combinations, constructions, and arrangements herein described and claimed.

5 An object of my invention is to provide a fastening device wherein novel means is employed for positively locking a window in any desired position.

A further object of my invention is to provide a device of the type described which has novel means for holding the window against lateral movement.

15 A further object of my invention is to provide a device of the type described which employs a fastening means for positively holding the window in any desired position against upward movement but which will allow the window to be moved downwardly at will.

20 A further object of my invention is to provide a device of the type described which is simple in construction, durable, and efficient for the purpose intended.

Other objects and advantages will appear 25 in the following specification, and the novel features of the invention will be particularly pointed out in the appended claims.

30 My invention is illustrated in the accompanying drawings, forming part of this application, in which

Figure 1 is a longitudinal sectional view of the window construction illustrating the novel fastening means.

35 Figure 2 is a front elevation of the window construction illustrating the fastening means, and

40 Figure 3 is a plan view of the fastening means shown in operative position in solid lines and out of operative position in dotted lines.

45 In carrying out my invention, I make use of a window frame 1 having longitudinally extending grooves 2 therein. A window 3 is provided with tongue portions 4 which are movably disposed in the grooves 2.

50 I provide a corrugated fastening strip 5 rigidly secured to the frame 1 at each end by means of screws 6 or the like. The fastening strip 5 is provided with transversely extending side portions 7. The fastening

strip is also provided with receiving grooves 8 and retaining shoulders 9.

A fastener 10 is pivotally mounted at 11 upon the window 3 and is provided with a hinge portion 12. A tension spring 13 is disposed concentric with the shaft 14 of the hinge portion 12. One end of the spring 13 bears against the base portion 15 of the fastener 10, and the other end bears against the movable portion 16.

The movable portion 16 is provided with an integral lip 17 at the outer extremity thereof which tapers inwardly to conform to the general contour of the locking strip 5 in cross section. The movable portion 16 is also provided with retaining ears 18 which are arranged to extend around the edges of the locking strip for a purpose hereinafter described. A handle or knob 19 is provided for the movable portion 16.

70 From the foregoing description of the various parts of the device, the operation thereof may be readily understood. Let us assume that the fastener 10 is in the position shown in solid lines. It is obvious that the tension spring 13 tends to force the movable member 16 into and hold it in close engagement with the fastening strip 5. In so doing, the lip 17 is received in one of the recesses 8 and abuts the adjacent retaining shoulder 9. 75 Therefore, any tendency to move the window 3 upwardly with respect to the frame 1 would tend to more firmly force the lip 17 into locking engagement with the fastening strip 5.

80 The window 3 may be moved downwardly, and, in doing so, the lip 17 of the movable member 16 will ride over the retaining shoulders 9 until the movement of the window has ceased. Then, if the window is forced upwardly, the lip 17 will be forced by the spring 13 into the adjacent recess 8 and against the adjacent shoulder 9. The retaining ears 18 extend upon each side of the fastening strip 5 for holding the movable member against lateral displacement. The ears 18 also hold 85 the window against lateral movement.

90 The fastener 10 may be freed from the fastening strip 5 by the operator's gripping the handle 19 and drawing the movable member 16 free from the fastening strip. 95 100

When the movable member 16 is freed from the fastening strip, the latch or lock 10 may be swung about the pivot 11 and allowed to remain in the dotted line position shown in Figure 3 out of engagement with the fastening strip.

I claim:

1. A device of the type described comprising a fastening strip having transversely extending side portions, a fastener, means for holding said fastener in engagement with said fastening strip, and ears integral with said fastener and extending substantially at right angles with respect thereto, said ears being adapted to be disposed upon each side of said fastening strip and to engage with said side portions irrespective of the movement of said fastener with respect to said fastening strip.
2. A device of the type described comprising a fastening strip having transversely extending side portions, a fastener, means for holding said fastener in engagement with said fastening strip, ears integral with said fastener and extending substantially at right angles with respect thereto, said ears being adapted to be disposed upon each side of said fastening strip and to engage with said side portions irrespective of the movement of said fastener with respect to said fastening strip, and means for pivotally supporting said fastener whereby said fastener may be moved out of engagement with said fastening strip.

Signed at Chicago, in the county of Cook, and State of Illinois, this 31st day of January, A. D. 1928.

ARTHUR J. SLINGERLAND.
